COMBINED WATER CLOSET TANK AND COVER

Jack Nelson Kaiser, Louisville, Ky., assignor to American Radiator & Standard Sanitary Corporation, New York, N.Y., a corporation of Delaware

Filed July 17, 1962, Ser. No. 70,967

Term of patent 14 years

(Cl. D4—5)

FIGURE 1 is a view in front elevation of a combined water closet tank and cover showing my new design;

FIGURE 2 is a top plan view thereof; and

FIGURE 3 is a view in side elevation looking from right to left facing FIGURE 1.

I claim:

The ornamental design for a combined water closet tank and cover, substantially as shown.
